UNITED STATES PATENT OFFICE.

ORA F. HAIBE, OF UNIONTOWN, PENNSYLVANIA.

INTERNAL-COMBUSTION MOTOR.

Application filed October 31, 1921. Serial No. 511,748.

To all whom it may concern:

Be it known that I, ORA F. HAIBE, a citizen of the United States, residing at Uniontown, county of Fayette, and State of Pennsylvania, have invented certain new and useful Improvements in Internal-Combustion Motors, of which the following is a specification, reference being had to the accompanying drawings.

Amongst the objects of my invention are to secure in internal combustion motors generally, a more thorough and intimate intermingling of the constituents of the gaseous fuel charge admitted to the cylinders, also to supplement the charge with additional air for the purpose of obtaining greater weight of the charge and consequently, higher explosive efficiency; and in internal combustion motors of the two cycle type, more efficient scavenging of the cylinders and displacement of substantially all the spent products of combustion.

Other objects and attendant advantages will become readily apparent from the detailed description of a typical embodiment of my invention which follows.

In the drawings, Fig. I is a longitudinal section of an internal combustion motor conveniently embodying my invention.

Fig. II is a cross sectional view of the same axially through the cylinder; and

Figs. III and IV are sectional views similar to Figs. I and II, showing the movable parts of the motor in different positions.

In the structure here represented, the cylinder of the motor is indicated at 1, and shown as enveloped by a jacket 2 for the circulation of a suitable cooling medium. The head 3 is preferably made integral with the cylinder and the jacketing is extended thereto, as clearly shown in the illustrations. The cylinder is formed with a base flange 4 so that it may be readily secured, by bolting or otherwise, to the top of the crank case indicated at 5.

Reciprocatory within the cylinder 1 are two concentrically arranged, power pistons 6 and 7, the former of which is in the form of an elongated sleeve headed at its upper end, while the latter is of ordinary construction and proportions. These pistons move in opposition to one another and are respectively connected to cranks 8—8 and 9 of the engine shaft 10 whose opposite ends have bearing in suitable journals 11, 11 forming part of the crank case 5. The sleeve piston 6

is coordinated with the cranks 8—8 by means of connecting rods 12—12, the upper ends of which are pivoted to appropriate studs 13 projecting from opposite sides of the lower end of said piston. The cylinder casting is bulged as at 15—15 for accommodation of the connecting rods 12 as best seen in Fig. I. The inner piston 7 is connected to the crank 9 by a single connecting rod 16. In practice the pistons and their appendages are respectively so designed as to be of equal weight so that the engine will operate in perfect balance at all speeds.

The fuel is drawn into the top of the cylinder 1 during the downward stroke of the sleeve piston 6 through an inlet 18 preferably centrally disposed in the head 3 of the cylinder and communicative with a passage 19 connected by a pipe 20 with a carburetor or other source of supply. The inlet 18 is controlled by a poppet valve 21, whose stem is acted upon by a spring 22, so as to be normally held closed, and actuated, through the instrumentality of a rocker arm 23 and push rod 24, by a cam 25, on a shaft 26 suitably journaled within the crank case. Said shaft is driven from the engine shaft at a synchronous speed, through the interposed gears 27, 28 and 29, see Figs. I and II. During the upward stroke of the sleeve piston 6 the fuel previously admitted to the space in the top of the cylinder, (which may for convenience be termed a compression chamber) is compressed until said piston reaches the top of its stroke when the fuel is permitted to escape by way of an annular space 30 formed within the cylinder head and through a multiplicity of registering ports 31 and 32 of the cylinder and piston respectively. It is to be especially noted that these ports are of very small diameter, and by virtue of this, the fuel, as it forces its way into the space or chamber intermediate the heads of pistons, is effectively diffused with the result that its constituents are thoroughly and intimately mixed. It is also to be noted that the ports 31, 32, are inclined downwardly so that the fuel is correspondingly directed to facilitate and hasten expulsion of the spent gases of a previous explosion in a two cycle motor as herein represented. Leakage to opposite sides of the ports 32 is prevented by provision of the piston rings 33—33.

At a region intermediate its ends the sleeve piston 6 has a port 34 by way of which the spent products of combustion escape

- through an opening 35 in the wall of the cylinder and into the exhaust pipe indicated at 36 when the parts of the motor are in the position shown in Figs. I and II.
- 5 The port 34, it will be observed, is preferably elongated somewhat as illustrated so that ample time is afforded to permit ready escape of the exhaust gases. At a point preferably opposite the exhaust pipe 36, the cylinder has an inlet 37 which communicates by way of duct 38 with the interior of the crank case. In the course of the reciprocation of the inner piston 7, air is first drawn into the crank case through an automatically operative inlet valve 39, and thence compressed so that when a port 40 in the piston 6 registers with the inlet 37 as shown in Fig. II, the compressed air is forcibly injected into the lower portion of 20 the cylinder and serves to assist in the discharge of the spent products of combustion. Referring again to Fig. II, it will be observed that the compressed air is not admitted until after the pistons 6 and 7 have 25 been separated to the maximum extent so that, by its influx any residue of the spent gases is quickly displaced and discharged through the port 34 and exhaust pipe 36, this action being facilitated by reason of the 30 opposite location of said port and the inlet 37. It is further to be observed that the fuel inlets 31 and the port 40 are opened at about the same time so that the incoming fuel and compressed air are cooperative in 35 effecting ejection of the spent gases, and moreover that the air serves to dilute the fuel to the attainment of a higher degree of efficiency in the combustibility of the mixture.
- 40 In the course of the motion of the pistons 6 and 7 toward each other, the fuel mixture now in the space or chamber between them is compressed. When the pistons have fully approached each other, the compressed 45 charge is exploded by the aid of the spark plug shown at 41 which is accommodated in an opening 42 in the cylinder wall, said opening registering, at the period under consideration, with an opening 43 directly 50 beneath the head of the piston 6 amongst the circle of inlets 32. In Figs. III and IV the pistons 6 and 7 are just about to reach the positions just described and the poppet valve 21 about to close to prevent further

admission of fuel to the top of the cylinder 55 1.

From the aspects of my invention as above described, it will be apparent that certain of its features are applicable to internal combustion motors other than the two cycle 60 type, and therefore I do not wish to limit myself to the precise details of construction and arrangement herein shown.

Having thus described my invention, I 65 claim:

An internal combustion engine of the type described comprising a crank case, a jacketed cylinder having an integral enlarged head end forming a fuel compression pocket with the jacketing extended thereover, a 70 fuel intake valve in said cylinder head, the cylinder wall having an exhaust port, said cylinder being extended into the pocket to form a flange, said flange having apertures communicating the pocket with the cylinder, a sleeve slidably fitted in the cylinder closed at its head end and having apertures for registration with the first mentioned apertures and communicating the pocket with the interior of the sleeve when the latter is at its inner position, a piston slidably fitted in the sleeve, a crank shaft having opposed offsets, a pitman connection between the piston and one offset, a pair of pitman connections between the other offsets and 80 sleeve, the cylinder wall having a passage for air connecting said cylinder with the crank case, said passage connecting with the inner bore of said sleeve through the medium of an aperture formed when the 85 piston is at the end of the power stroke and the sleeve is simultaneously at the end of the compression stroke and in communication with the fuel compression pocket, a spark plug mounted in a recess in the cylinder wall, the sleeve having openings for registration with the spark plug recess and exhaust port, an intake valve opening into the pocket, and means for operating said intake valve.

In testimony whereof, I have hereunto signed my name at Philadelphia, Pennsylvania, this 20th day of October, 1921.

ORA F. HAIBE.
